UNITED STATES PATENT OFFICE

ALBERT F. DORMEYER, OF CHICAGO, ILLINOIS

DESIGN FOR AN ELECTRIC-MOTOR-UNIT CASING OR SIMILAR ARTICLE

Application filed November 11, 1929. Serial No. 33,411. Term of patent 14 years.

To all whom it may concern:

Be it known that I, ALBERT F. DORMEYER, a citizen of the United States, residing at Chicago, in the county of Cook, and State of Illinois, have invented a new, original, and ornamental Design for an Electric-Motor-Unit Casing or Similar Article, of which the following is a specification, reference being had to the accompanying drawings, forming part thereof.

Fig. 1 is a front elevational view of the

electric motor unit casing showing my new design.

Fig. 2 is a top plan view of the design.

Fig. 3 is a bottom plan view of the design.
I claim:

The ornamental design for an electric motor unit casing, or similar article as shown.

In witness whereof, I hereunto subscribe my name this 5th day of Nov., 1929.

ALBERT F. DORMEYER.
